UNITED STATES PATENT OFFICE.

ALBERT EDWARD SIMONS, OF BRANTFORD, ONTARIO, CANADA, ASSIGNOR TO HAPPY THOUGHT FOUNDRY COMPANY LIMITED, OF BRANTFORD, CANADA.

STOVE.

Application filed January 3, 1928, Serial No. 244,196, and in Canada July 6, 1927.

The principal objects of the invention are to devise a stove particularly designed for apartment heating purposes, of simple and inexpensive construction and remarkably efficient in its heating qualities and which presents an attractive appearance.

The principal features of the invention consist in the novel construction of an inner refractory lined sheet metal structure and 10 an outer casing enclosing a heating chamber open at the bottom and provided with openings in the side walls through which the heated air is directed laterally outward.

In the drawings, Figure 1 is a perspective view of a stove constructed according to this invention having a portion of the outer casing broken away.

Figure 2 is a vertical mid-sectional view of the stove taken from front to back.

Figure 3 is a vertical sectional view 20 through one of the sides of the stove.

Figure 4 is a horizontal sectional view of the stove taken on the line 4—4 of Figure 2.

In the construction herein shown the outer 25 casing 1 of the stove is formed with the sheet metal side walls 2 flaring slightly to the top and the bottom edges are turned inwardly to form the flanges 3. The back sheet 4 is formed similar to the side walls 30 and is provided with inturned edge flanges 5 which are preferably spot-welded to the side walls.

The back corner legs 6 are formed with horizontal flanges 7 upon which the flanges 3 of the sides 2 rest and side flanges 8 extend upwardly and embrace the outer sides of the casing and are secured thereto by bolts 9.

The front legs 10 are formed with upright 40 flanges 11 arranged in acute angular relation and a bar 12 having right angularly bent ends 13 extends between said front legs and is bolted thereto by the bolts 14.

A bar 15 having horizontally offset ends 45 16 bolted on the inner side of the casing to the back legs extends parallel with the front bar 12.

A rectangular sheet metal casing 17 rests upon the bars 12 and 15 and is spaced from 50 the side and back walls.

The front sheet 17' of the inner casing is formed with outwardly flaring side flanges 18 which extend to meet the flaring front edges of the side walls 2 and the meeting

edges are embraced by the cast metal edge 55 members 19.

The top portions 20 of the side and back members 2 and 4 are flanged inwardly at an obtuse angle and the upper edges are flanged downwardly and inwardly and are 60 secured to the horizontal outwardly turned flanges 21 of the inner casing.

A cast iron top 22 rests on these top flanges and is secured thereto by bolts 23. The top 22 is provided with a smoke pipe 65 thimble 24 and a removable cover 25.

A flanged metal sheet 26 closes the bottom of the inner casing and intermediate of the height of said inner casing is secured a cast metal frame 27 which supports the 70 grates 28 and also carries the refractory fire bricks 29 which line the upper part of said inner casing and form the fire box.

A fire door and frame 30 is arranged in the upper part of the front sheet 17' and an 75 ash door 31 gives access to the space below the grates.

The side walls 2 are formed with openings 32 adjacent to the top and frames 33 provided with suitable grilles or bars 34 are 80 secured in said openings.

Air enters at the bottom of the space between the inner and outer casings and flows upwardly around the hot inner casing and striking the top flanges 20 of the sides it 85 is directed outwardly to heat the apartment in which the stove is placed. This construction is very effective in circulating the heated air and the open grilles in the side walls allow the radiant heat waves to flow 90 directly outward from the inner casing.

The outer casing being spaced from the inner casing on the back and sides prevents contact with highly heated surfaces and the front is recessed back and protected by the 95 forwardly projecting flanges 18.

The whole construction is light in weight, being mainly formed of sheet metal, it is highly efficient in disbursing heat and is of a very attractive design.

100

What I claim as my invention is:—

1. A stove, comprising a rectangular refractory lined casing having the front side thereof provided with flaring side flanges projecting forwardly and laterally from the front thereof, a casing formed of a pair of flaring sheet metal sides and a flaring sheet metal back secured at its forward edges to

the free edges of the flaring flanges of the inner casing and spaced from said inner casing leaving the front side of the inner refractory lined casing exposed at the bottom 5 of the recess formed by said flaring side flanges, flanges closing the space between the inner and outer casings at the top and being connected with said inner casing, and openings in the outer casing below the 10 flanges.

2. In a stove, the combination with an open bottomed casing of sheet metal having legs secured to the lower end thereof and supporting the casing above the floor, of a 15 pair of parallel bars having offset ends secured to said legs, a casing of sheet metal resting on said parallel bars and spaced from said outer casing and having a refractory lining, flanges extending inwardly 20 from the outer casing and rigidly connected to the top of the inner casing, a top closing the inner casing, and openings formed in the ends of the outer casing below the 25 flanges.

3. A stove having an outer casing open at the bottom and flanged inwardly at the top and having openings in the side walls adjacent to the top and extending substantially the full width thereof, a refractory 30 lined casing supported within said outer casing and spaced therefrom, the top thereof meeting the inwardly turned top flanges of said outer casing and closing the space surrounding the inner casing at the top, and

open grilles arranged in said side openings. 35

4. A stove having an outer sheet metal casing of substantially rectangular cross section having its side and rear walls diverging upwardly, said casing being open at the bottom, an inner refractory-lined casing supported within said casing and having its upper end spaced above the top of said rectangular casing, baffle flanges extending angularly upward from the upper end of said diverging casing walls and rigidly connected 40 to the top of said inner casing, and openings extending across the convergent side walls of the outer casing immediately below said baffle flanges.

5. A stove having an outer sheet metal 50 casing of substantially rectangular cross section having its side and rear walls diverging upwardly, said casing being open at the bottom, an inner refractory-lined casing supported centrally within said outer casing, the upper portion of said diverging casing walls being flanged angularly inward from a point below the level of the top of the inner casing, said flanged portions being rigidly secured at their inward edge to the 55 top of the inner casing and closing the top of the chamber formed between said inner and outer casings, rectangular openings extending across the convergent side walls of the outer casing immediately below the inwardly flanged upper portion thereof, and grilles fitting in said openings.

ALBERT EDWARD SIMONS.
